WARDROBE TRUNK

Application filed November 5, 1928. Serial No. 317,403.

This invention relates to improvements in wardrobe trunks.

One of the objects of this invention is to minimize the frictional resistance incident to opening a wardrobe trunk, which resistance is due to the frictional drag of the opening or cabinet section on the carpet or floor.

In accordance with my invention, the opening structure of the trunk is made in a plurality of sections which may be serially swung into an open position.

A special feature of the invention resides in dividing the opening structure, which, with the back structure, comprises the trunk, into a relatively small controlling section and a relatively large opening section, said sections being in superposed relation and the controlling section being lowermost.

A further feature of the invention consists of a lower or controlling section which not only performs its normal function as such, but which also acts as a stabilizing means when adjusted into various angular positions with respect to the remainder of the trunk structure.

The invention also includes a novel stabilizing means, which in one phase of the invention takes the form of an automatic device which always functions to stabilize the trunk when a portion thereof is opened, and which, in another phase of the invention takes the form of a manually actuatable device which may or may not be employed, dependent upon the will of the user.

A further feature of the invention resides in a novel subdivision of the opening structure into a plurality of sections so formed or so equipped with means whereby only a predetermined section may first be opened.

A further feature resides in the provision of means whereby the closing of one predetermined section will move the remaining section into a closed position.

A still further feature consists in equipping the adjacent ends of the swinging sections with closed end walls that jointly contribute to closure of the sections into tight relation when said sections are moved into a closed position.

The invention has many other objects and

features which will be more fully described in connection with the accompanying drawings and which will be more particularly pointed out in and by the appended claims.

In the drawings;

Fig. 1, is a view in elevation of the improved trunk looking at the outer face of the opening structure.

Fig. 2, is a view in side elevation looking at the lock side of the trunk and showing the controlling section open to illustrate the overbalanced and over-hanging section that is closed.

Fig. 3, is a view in elevation looking at the hinged side of the trunk.

Fig. 4, is a plan view showing how the controlling section may be angularly disposed in a manner to stabilize the trunk structure.

Fig. 5, is a view similar to Fig. 1, on an enlarged scale, and showing the controlling section fully opened and the automatic stabilizing device in an operative position.

Fig. 6, is a view similar to Fig. 5, with the remaining section of the opening structure swung into an open position.

Fig. 7, is a sectional view on line 7—7 of Fig. 6, showing the automatic stabilizing device in a projected position in full lines and in a retracted position in dotted lines.

Fig. 8, is a sectional view on line 8—8 of Fig. 6, looking toward the right and showing the stabilizing device in a projected position.

Fig. 9, is an enlarged sectional view on line 9—9 of Fig. 1.

Fig. 10, is a sectional view looking to the right of Fig. 11, showing a modified form of stabilizing device in an operative position in full lines and in an inoperative position in dotted lines.

Fig. 11, is a sectional view on line 11—11 of Fig. 10, looking toward the left of said figure.

Fig. 12, is a front elevation looking toward the left of Fig. 10.

Like characters of reference designate similar parts throughout the different figures of the drawings.

First referring to Figs. 1 to 8, there is shown a wardrobe trunk having a back, which I will term a back compartment or

55

60

65

70

75

80

85

90

95

100

structure 1, the same having an outer face 2, a lock side 3 and a hinged side 4. The locks, which may be of any type, are indicated at 5 and 6, and the hinges at 7 and 8. In the 5 interior of this back structure 1, will be the usual hangers (not shown) and in the lower portion, is a compartment 9, formed by the face wall 2 and a wall 10. The bottom wall of the structure 1, is indicated at 11, and a 10 false bottom 12 forms a space 13 into which a stabilizing device is adapted to be retracted, as will later appear.

What is usually the cabinet or drawer portion of a wardrobe trunk is what I will term 15 the opening compartment or structure and in the present invention, this opening structure comprises a plurality of sections, preferably two in number, and generally designated at 14 and 15. The former section is 20 termed the opening section and comprises an outer face portion 16, a hinged side 17 and a lock side 18. The locks 5, coact to secure and hold the opening section closed against the back structure and said section 14 is 25 adapted to swing about an upright axis formed by the hinges 7. It will be noted that the opening section 14 is not only the upper section, as shown, but it is also the larger of the two sections, and in Fig. 6, I 30 have shown the same provided with a plurality of drawers designated at from 19 to 22. The lower wall 23, of section 14, is inclined to what would be the horizontal, when the trunk is in the normal wardrobe position as 35 shown in Figs. 1 to 3. This inclination of wall 23 is an important feature which will be hereinafter more fully explained.

The remaining section 15, of the opening structure, is what I will term the controlling 40 section and the same comprises an outer face 24, a hinge side 25 and a lock side 26. This section 15 is connected with hinges 8, to swing about an upright axis and locks 6, to serve to hold this section closed against the 45 back structure. Section 15 has a bottom wall 27 and a false bottom 28, a space 29 being formed between the two to accommodate an actuating means for the stabilizing device to be later described. The upper wall 30, of 50 section 15, is inclined as shown in Fig. 9, in the same direction and manner as wall 23, of section 14.

Thus it will be clear that the bottom of 55 section 14 and the coacting top of section 15, are each closed by their respective walls, as shown, and further, these walls 23 and 30 jointly coact to render these two sections practically as one, when they are closed against the back structure 1, the two walls 60 coming into abutting relation and thereby rendering the two sections effectively rigid when closed. Of course, in the performance of this function, the hinges and locks play an important part but they, alone, could play 65 no such part in the absence of the inclined

planes at which said walls 23 and 30 are disposed.

Now a further phase of this inclination of 70 walls 23 and 30 is that they are specifically inclined in such a manner and at such an angular disposition that the sections 14 and 15 must be opened successively, or at least, one section must be moved toward an opening position before the other can be opened. In the present construction, it is a feature of 75 the invention to so dispose the inclination of walls 23 and 30 that the section 15, must first be opened before section 14 can be opened, and further, it is a feature that when section 15 is closed, it will automatically close section 14.

It will now be clear why I term section 15, 80 the controlling section. However, this section performs another important function which will be fully understood by reference to Figs. 2 and 4. It will be seen from Fig. 2, that when the controlling section 15 has been swung open, that section 14 overhangs the back structure and would render the trunk unstable. This can be the more readily understood when it is considered that often the drawers 19 to 22 are packed with material or clothing that greatly outweighs the contents of the back section 1.

Therefore, the controlling section may be 85 swung into any angular relation to back structure 1, for instance as shown in Fig. 4, in which position the controlling section will be readily accessible as regards its interior, and at the same time, it will prevent the trunk from tilting or falling to the right of Fig. 2. Even when the section 14 is also 90 opened, it can be disposed in the general relation shown in Fig. 4, and both sections will be accessible as regards their interiors, and at the same time, the trunk will be held stable. Thus it will be seen that in the total absence 95 of stabilizing devices which I will later describe, the trunk as thus far disclosed, is a completely operative and advantageous structure. At this point, it may be stated 100 that in practice, I will make the section 15 sufficiently large to render its interior useful, and as shown, I have provided the same with a drawer 31, as an example, having a lock 105 31' so that the controlling section may form 110 a complemental part of the opening structure.

The fact that the walls 23 and 30 abut, 115 will, in itself alone, act effectively to prevent 120 ingress of foreign matter to the interior of the trunk but I have provided a further means for the performance of this function that is not only effective as regards dust but also rain, and which, in the event that sections 14 and 15, should, after wear, tend to 125 sag away from each other, will supplement the function of the walls 23 and 30.

Said additional means, as shown, includes 130 an upstanding flange mounted on the upper

edge of section 15, and having a portion 32 that extends along the hinge side 25 and a section 33, that extends along the outer face 24, of section 15. This flange extends upwardly 5 far enough to overlap the corresponding or complementary faces of the section 14. Section 14, has a flange 34, that extends downwardly in overlapping relation with the corresponding lock side 26, of section 15 thereby effectively closing the same against ingress 10 of dust to the interior, or rain either. This disposition of the flanges 32, 33 and 34 is such that they do not interfere with consecutive opening of the sections and the flanges 15 32 and 33 act to insure closure of section 14 when section 15 is closed. However, as a further precautionary measure, I extend flange 34, as indicated at 35, inwardly along the inner face of section 14 so that when the 20 sections are closed, there will be outer and inner flanges in spaced relation, acting in supplemental relation to prevent ingress of foreign matter to the trunk.

I preferably extend the flange 35 far 25 enough down, or dispose the wall 10 far enough upwardly so that when it is desired to lock section 14 closed, without closing section 15, all of the interior of the back section 1, and the section 14, will be entirely inaccessible from the exterior, as will be clear from 30 Fig. 5. This flange 35, also insures opening of the controlling section 15, if and when it is desired to open both sections simultaneously, as it will be readily apparent that section 15 could not stay closed, by reason of flange 35, when section 14, is swung open.

Reference will next be made to the preferred form of stabilizing device shown in Figs. 6 to 8.

40 A stabilizing member 36 is suitably pivotally mounted at 37, in space or chamber 13, in a manner clearly shown in Fig. 7. This member which may be in the form of a plate of the form shown, is of sufficient length so 45 that when it is projected, as shown in Fig. 8, it will extend outwardly from back structure 1. Said member is provided with a floor engaging stud 38, projecting downwardly therefrom so that when the member is projected, the stud 38 will engage the floor and, 50 as will now be clear, the range of floor support for the back structure 1, will be extended practically the depth of said section, or once again, thereby preventing the trunk 55 from tilting to the right of Fig. 2, either when section 14 is closed or opened to the fullest extent. I have provided recesses 39 and 40, in the walls 11 and 27, respectively, so that the stud 38 will be received therebetween 60 when the sections are closed, as shown in dotted lines in Fig. 7.

Means is provided for automatically projecting the stabilizing member 36, when section 15 is swung open, which means I will 65 next describe in detail.

Said means is in the form of a link connection of the break joint type, and as shown, I pivot a link 41, at 42, on said member 36. An actuating link 43, is pivoted at 44, to section 15 and the remaining end is pivoted at 45, to link 41. A stud or pin 46, mounted on member 36, prevents the links from breaking joint in a manner reverse from that shown in Fig. 7. As section 15 is swung open, it will now be clear how member 36 is projected into an operative position, and in dotted lines, I have shown the position of the parts when section 15 is closed against the back structure 1.

It will now be clear that just as soon as 50 section 15 has been swung open, the stabilizing means is, or becomes fully operative to stabilize the trunk irrespective of the position of section 14, and it will also be clear that by employing this stabilizing means, the 55 sections 14 and 15 can be swung into a full open position.

As an alternative form of stabilizer, I have provided means which is manually operative both toward and from an operative position 60 so that such means may be selectively employed when desired.

As shown, and referring more particularly to Figs. 10, 11 and 12, 47 designates a thin strip metal or like arm that I prefer to make 65 of spring steel, and I have shown the same pivoted at 48, to the interior of section 1. Said arm is suitably bent to form a stabilizing foot 49, adapted when in the operative position shown in Fig. 11, to engage the floor, 100 as also shown in Fig. 10. An abutment 50, is fixed to the side wall of section 1 and has a shoulder 51 projecting therefrom as shown. When arm 47 is adjusted to the position 105 shown in Fig. 10, it can be laterally shifted under and into engagement with shoulder 51, whereby any thrust of tilting movement of the trunk to the right of Fig. 2, would be imposed upon said arm and arrested. It will be noted that the foot 49 extends over the 110 outer edge 52, of section 1, so that the foot will engage the floor for its entire area. When it is desired to retract the stabilizer, it is shifted laterally from under shoulder 51 and backwardly, as shown in dotted lines 115 in Fig. 10. A retaining stud or pin 53, may be provided for engagement with an aperture 54, in arm 47, to hold the latter in a retracted position.

It will now be clear that by slightly tilting 120 the trunk in the direction of the arrow *a* of Fig. 2, if such is necessary, the lower or controlling section 15, after being unlocked, can readily and easily be swung into an open position before section 14 has even been unlocked. Thus it will be clear that after a guest at a hotel once opens section 15, it can be left open, and the drawer thereof locked by lock 31'. Section 14 will thereafter be 125 free to be opened as easily as a door on 130

hinges. When section 14, is closed and locked, with section 15 open, all the contents of section 14, and the back structure, as will now be clear, will be entirely inaccessible from the interior.

5 It is believed that the device of this invention will be fully understood from the foregoing, and while I have shown and described specific forms thereof, I do not wish 10 to be limited thereto except for such limitations as the claims may import.

I claim:

15 1. A wardrobe trunk comprising a back compartment, and an opening compartment movable toward or away from said back compartment about an upright axis, said opening compartment comprising an upper opening section and a lower controlling section, and said controlling section being movable 20 into an angular stabilizing position with respect to said back compartment to stabilize the latter while said opening section is closed.

25 2. A wardrobe trunk comprising a back structure, an upper opening section and a lower controlling section hinged to said back structure to swing about an upright axis, said controlling section having an upwardly extending flange disposed along the hinged side and along the outer face of said section, for 30 engagement with corresponding portions of said opening section, and said opening section having a downwardly extending flange disposed along its interior face and along its lock side for engagement with corresponding 35 portions of said controlling section, whereby closing of said controlling section will insure closing of said opening section and form interior and exterior closure means against ingress of dust or other foreign matter into said trunk between the line of junction 40 of said sections.

45 3. A wardrobe trunk comprising a back structure, an upper opening section and a lower controlling section hinged to swing about an upright axis, said controlling section having an upwardly extending flange disposed along its hinged side and along its outer face for engagement with corresponding 50 portions of said opening section, and said opening section having a downwardly extending flange disposed along its lock side for engagement with a corresponding side of said controlling section, thereby providing an exterior means for preventing ingress of 55 foreign matter to the interior of said trunk.

60 4. A wardrobe trunk comprising a back structure, a section hinged to said structure to swing about an upright axis and rendering the trunk unstable when said section is opened, and a trunk stabilizing device movable into and out of an operative position by opening and closing movement respectively of said section.

65 5. A wardrobe trunk comprising a back structure, a section hinged to said structure

to swing about an upright axis, a trunk stabilizing device movably mounted on said back structure, and means connecting said device with said section to project said stabilizing device into an operative position when said section is opened and retract said device into said structure when said section is closed.

70 6. A wardrobe trunk comprising a back structure, a section hinged to said structure to swing about an upright axis, a trunk stabilizing device hinged to said structure to swing in a substantially horizontal plane near the bottom thereof and adapted for engagement with the floor on which said trunk is disposed, and link means connected with said device to project the latter into an operative position with the floor when said section is opened and retract said device into said structure when said section is closed.

75 7. A wardrobe trunk comprising a back structure, a section hinged to said structure to swing about an upright axis, a trunk stabilizing device hinged to said structure near the bottom thereof and having a floor 80 engaging stud, and means connected with said section for projecting said device into an operative position with said stud in engagement with the floor when said section is opened.

85 In witness whereof, I have hereunto set my hand.

GEORGE P. CRAGIN.
